UNITED STATES PATENT OFFICE.

WILLIAM M. TULLEY, OF CORPUS CHRISTI, TEXAS.

VALVE SILENCER.

Application filed October 27, 1921. Serial No. 510,743.

To all whom it may concern:

Be it known that I, WILLIAM M. TULLEY, a citizen of the United States, residing at Corpus Christi, in the county of Neuces and 5 State of Texas, have invented certain new and useful Improvements in Valve Silencers; and I do declare the following to be a full, clear, and exact description of the invention, such as will enable others skilled 10 in the art to which it appertains to make and use the same.

My invention relates to improvements in valve mechanisms for internal combustion engines and has reference more particularly 15 to valve silencers to prevent the undesirable noise which often occurs, particularly in connection with overhead valves.

Referred to more specifically, my invention includes a coiled cushioning spring associated with the tappets and the push-rods for continually exerting pressure on all of the valve operating connections, so as to take up any lost motion which would otherwise cause noisy operation of the valve 25 mechanism. I am aware that devices for this purpose have heretofore been devised but it is the aim of my invention to provide an extremely simple and inexpensive, yet a highly efficient and desirable article which 30 may be quickly and easily attached to internal combustion engines of the common types now on the market.

With the foregoing in view, the invention resides in the novel subject matter herein- 35 after described and claimed, the descriptive matter being supplemented by the accompanying drawings.

Figure 1 is a side elevation of a portion of an automobile engine, showing a vertical 40 sectional view of my invention attached thereto.

Figure 2 is a side elevation of the attachment removed from the push-rod.

Figure 3 is a horizontal sectional view as 45 indicated by line 3-3 of Fig. 2.

In the drawing above briefly described, the numeral 1 designates a portion of a well known form of internal combustion engine having the usual overhead valves, one of 50 which is designated by the reference numeral 2, said valve being closed upwardly in the usual manner by means of a coiled spring 3. A rocker 4 is pivotally mounted upon the cylinder head and at one end is provided 55 with a socket 5 receiving a ball 6 on the upper end of a push-rod 7, said ball pref-

erably having a detachable threaded connection with the push-rod which also permits adjustment when necessary. The lower end of the push-rod 7 is removably received in a socket 8 in the upper end of the tappet 9 which is operated by the well known cam 10. All of this construction is well known and is merely shown as illustrating one form of valve mechanism in connection with 60 which my invention may be used. It will be understood however, that the attachment hereinafter described is not restricted to use upon any particular make of engine and that furthermore while the device is here 65 shown associated with a valve push-rod and its tappet, it might in some instances co-act with a tappet and a valve stem with which the tappet directly contacts.

The numeral 11 designates a thrust-collar 70 which is preferably secured upon the push-rod 7 in the manner shown, said collar being in contact with the upper end of a coiled compression spring 12 whose lower end may rest directly on the tappet 9 or be provided 75 with a cup-washer 13 resting on said stem as shown. The collar 11 is preferably provided with a non-split head 14 of hexagonal or other suitable shape to be held by a wrench. From the head 14, a tapered externally threaded sleeve 15 extends, said sleeve being radially split at several points as indicated at 16, so that by threading a nut 17 along the taper of the sleeve, the latter may be tightly contracted and frictionally held upon the push-rod or the like 80 85 90 95 like 7.

When the device is applied with the spring 12 under sufficient compression, it will take up all slack in the valve-operating 95 connections and will consequently prevent noisy operation thereof.

While the details disclosed are preferably followed, it is to be understood that numerous minor changes may be made within 100 the scope of the invention as claimed.

I claim:

1. An attachment of the character described comprising a collar externally threaded and having a longitudinally extending unthreaded rod receiving passage, said collar being split longitudinally from one end to a point adjacent the other end, the unsplit portion of said collar being provided with wrench engaging faces and the 105 unsplit end portion of the collar having its end face provided with a spring seat, a 110

spring for fitting in the spring seat, a cup washer for engaging the other end of said spring, and a securing nut upon the collar for drawing the split portion thereof into a tight binding engagement with a valve rod.

2. An abutment for a valve silencing spring comprising a collar externally threaded and having a longitudinally extending unthreaded rod receiving passage,

said collar being split from its upper end to a point in spaced relation to its lower end and having its lower end portion provided with wrench-engaging faces, the lower end of said collar being provided with a spring receiving seat.

In testimony whereof I have hereunto set my hand.

WILLIAM M. TULLEY.
